UNITED STATES PATENT OFFICE.

BURNHAM C. STICKNEY, OF ELIZABETH, NEW JERSEY, ASSIGNOR TO UNDERWOOD COMPUTING MACHINE COMPANY, OF NEW YORK, N. Y., A CORPORATION OF NEW YORK.

TYPE-WRITING MACHINE.

1,257,546.

Specification of Letters Patent. Patented Feb. 26, 1918.

Original application filed December 13, 1910, Serial No. 597,117. Divided and this application filed December 16, 1916. Serial No. 137,281.

To all whom it may concern:

Be it known that I, BURNHAM C. STICKNEY, a citizen of the United States, residing in Elizabeth, in the county of Union and 5 State of New Jersey, have invented certain new and useful Improvements in Type-Writing Machines, of which the following is a specification.

This invention relates to typewriting machines, and more particularly to means for 10 shifting the ribbon mechanism, so that different stripes or fields of the ribbon may be rendered ineffective. This application is a division of my application No. 597,117, 15 filed December 13, 1910, (now Patent No. 1,237,258.)

I have provided that certain of the tabulating keys for the typewriter carriage shall be capable of shifting the ribbon mechanism, 20 so that the types shall print red, or any other special color.

The present improvements are illustrated in connection with column skipping, or 25 column selecting keys, but it will be understood that the invention may be carried out in connection with other kinds of tabulating mechanism.

Other features and advantages will hereinafter appear.

30 In the accompanying drawings,

Figure 1 is a sectional side elevation of the forward portion of the tabulating key levers, showing one of the keys depressed and as having effected a movement of the 35 shifting ribbon mechanism to print on the red stripe or field of the ribbon.

Fig. 2 is a sectional side elevation of an Underwood typewriting machine with the ribbon mechanism set to print on the black 40 stripe or field.

Fig. 3 is a part sectional rear elevation of the typewriting and tabulating mechanisms.

In the Underwood machine, keys 1 depress levers 2 to vibrate bell cranks 3, and 45 swing type bars 4 up to strike rearwardly against the front side of a platen 5. Said platen is mounted on a carriage 6, running on tracks 7, 8, and is driven by a spring barrel 9, and also has a rack 10 meshing with 50 a pinion 11 connected to an escapement wheel 12, the escapement dogs being seen at 12a. The rack 10 is hung on arms 13, so that it may be lifted from the pinion 11 to release the carriage.

Tabulator keys 14 are mounted upon levers 15, which, at their rear ends, raise stop-rods 16, having stops 17 at their upper ends. These stops may coöperate with interchangeably adjustable column stops 18, inserted, as required, in notches 19, 20, formed in the 60 top and bottom of a bar 21, which is fixed to the carriage 6.

Each stop-rod has a shoulder 22 coöperating with a universal bar 23, which rocks about a pivot 24, and has an arm 25, which 65 draws down a link 26 and vibrates a lever 27, the latter fulcrumed at 27a and carrying a roll 27b to run upon the under side of the rack bar 10, and lift the latter from the escapement pinion 11, whenever a key 14 is 70 depressed.

In the present instance each of the tabulating keys 14 is a column-selecting key, and, when depressed, serves to bring the carriage 6 to a predetermined column. One manner 75 of effecting this kind of tabulating consists in having the stop-rods 16 of assorted lengths, and having the column stops 18 of assorted depths, so that, the strokes of the stop-rod being uniform, each rod coöperates 80 with its associated stop, regardless of the position of the latter along the rack. The first stop-rod 16 in the series (the rod at the extreme right at Fig. 3) is preferably the longest, to engage the first column stop 18. 85 The next stop-rod 16 is too short to catch the first stop 18, but is long enough to catch the second stop 18; and so on.

The connection between the tabulating keys and the ribbon mechanism, which will 90 hereinafter be explained, comprises a horizontal rock-shaft 80, extending across the machine beneath the tabulating key levers 15 and forward of the fulcrum 81 of the latter and suitably supported upon the framework. This rock-shaft 80 may be rocked by means of forward and rear universal bars 82, 83, fixed upon the two pairs of arms 84, 85, extending forwardly and rearwardly from the ends of said rock-shaft, the whole 100 making a rocking frame.

Certain of the tabulating key levers 15 have downwardly extending projections or toes 86 forward of the rock-shaft 80 and overlying the universal bar 82, so that when 105 any one of said certain keys is depressed, the rocking frame is rocked to the position seen at Fig. 1. Certain other of the tabulat-

ing key levers 15 are provided in rear of the rock-shaft 80 with downwardly extending projections 102 to depress the universal bar 83 and turn the entire rocking universal bar or frame to the position seen at Fig. 2.

The usual bichrome ribbon mechanism of an Underwood typewriting machine comprises a universal bar 108 operated by heels 109 of the type bars and connected to the 10 dogs 12^a which feed the paper carriage 6. Upon said universal bar is fixed a bracket 110 which carries a slotted actuator 111 to engage one of two wrists 112, 113, upon a lever 114, to which is pivoted an upstanding 15 ribbon carrier 115 in front of the platen. The actuator 111 is usually two-armed, and by shifting the same on the bracket 110, the actuator is moved alternately into and out of engagement with one or the other of the 20 wrists 112 and 113 on the levers 114. This shifting of the actuator 111 is usually effected by a link 116 pivoted at 117 to an arm 118 extending up from a horizontal rock-shaft 119 which extends forwardly and carries at 25 its forward end a two-armed lever 120 having keys 121, 122, and also having a detent 123 to engage a V-spring 124, whereby the lever is held in position. The keys 121 and 122 are able to be effective because of the lost 30 motion of the tabulator key levers 15 before their lugs strike the universal bars 82, 83.

To this bichrome mechanism is connected a link 125, the latter having at its upper end a slot 126 to engage a pin 127 upon the lever 120. The link is pivoted at its lower end at 128 to an arm 129 fixed upon the rock-shaft 80.

When the parts are in the position seen at Figs. 2 and 3, the ribbon mechanism is in 40 position to expose the black stripe of the ribbon to the action of the types; the actuator or yoke 111 being connected to the upper wrist 112; but when any tabulator key with a projection or toe 86 is depressed, as at Fig. 1, the link 125 is thrust up, thus rocking the lever 120 and the rock-shaft 119, and vibrating the arm 118 through the link 116, shifting the actuator 111 so that the lower wrist 113 is connected to said actuator, and thus the lever 114 is vibrated at each stroke enough to carry up the red or special stripe of ribbon to be struck by the types.

After depressing and releasing any tabulating key 14, the rocking frame 82, 83, etc., of course, remains in the position to which it has been set by said key, and until another tabulating key is operated, unless a key 121 or 122, as the case may be, is operated; but, 60 of course, the invention is not limited to a tabulating mechanism of this character and operation.

Variations may be resorted to within the 65 scope of the invention, and portions of the improvements may be used without others.

Having thus described my invention, I claim:

1. In a typewriting machine, comprising a carriage, and also comprising a ribbon mechanism shiftable to cause different ribbon stripes to cover the printing point, the combination with tabulating devices including keys and devices connected to the typewriter carriage, of means connected to be operated by said keys to shift said ribbon mechanism. 70

2. In a typewriting machine, comprising a shiftable ribbon mechanism and a carriage, the combination with tabulating devices connected to the carriage, and including a set of independently operable keys, of means for enabling one of said tabulating keys to shift said ribbon mechanism, and for enabling another of said keys to restore said ribbon mechanism to its first position. 75

3. In a typewriting machine, the combination of a ribbon mechanism, a ribbon-shifter, a carriage tabulating mechanism including column-selecting keys, means whereby the column-selecting keys may operate said ribbon-shifter, and means whereby said shifter 90 may be manually operated irrespective of setting by said column-selecting keys. 85

4. In a typewriting machine, comprising a shiftable ribbon mechanism, a carriage, and column-selecting tabulator mechanism 95 therefor, the combination with a set of independently operable column-selecting keys forming part of the tabulator mechanism, of an element movable by certain of said keys for shifting said ribbon mechanism, and 100 means for enabling another of said column-selecting keys to restore the ribbon mechanism to its original condition.

5. The combination of a typewriter carriage, a tabulator mechanism for said carriage including a set of keys, a bar operable by any of a plurality of said keys, and a shiftable ribbon mechanism also connected to said bar. 105

6. The combination with a typewriter carriage, of a tabulating mechanism for said carriage, said tabulating mechanism including a series of keys, a member movable in one direction by certain of said keys and in the opposite direction by another of said 115 keys, and a shiftable ribbon mechanism also connected to said movable member.

7. The combination with a typewriter carriage, of a tabulating mechanism including a series of key levers a universal bar or frame 120 extending along said series of key levers, certain of said key levers constructed to engage the forward portion, and certain of said key levers constructed to engage the rear portion of said universal bar, to move the latter in 125 opposite directions, and a shiftable ribbon mechanism also connected to said universal bar.

8. In a typewriting machine, the combination with a shiftable ribbon mechanism and 130

- tabulator key levers, of means mounted on said key levers for positively shifting the ribbon mechanism to either of two color-printing positions.
- 5 9. In a typewriting machine, the combination with a carriage and tabulator key levers therefor, of a polychrome ribbon, and means on said key levers which determines in what color the typewriter shall write. 70
- 10 10. In a typewriting machine, the combination with a carriage and tabulator key levers therefor, of a polychrome ribbon, and individual means on each key lever which determines in what color the typewriter shall 75 write.
11. In a typewriting machine, the combination with a carriage and column-selecting key levers therefor, of a polychrome ribbon, said key levers being associated with ribbon shifting means in such a way that the actuation of different key levers will shift the ribbon mechanism so that different colors may be exposed to the printing point, and means for exposing said ribbon to the printing 80 point. 85
12. In a typewriting machine, the combination with a carriage and tabulator key levers therefor, of a polychrome ribbon shifting mechanism including a shiftable frame comprising parallel bars, said key levers engaging with said bars to set said ribbon mechanism to expose different colors to the printing point, the setting of said ribbon mechanism being dependent upon the position of said parallel bars. 90
13. In a typewriting machine, the combination with a carriage and tabulator key levers therefor, of a polychrome ribbon shifting mechanism including a shiftable frame comprising two bars, certain of said key levers engaging with one of said bars to set the ribbon mechanism for one color, the other key levers engaging with the other bar to shift the ribbon mechanism for the other 95 color.
14. In a typewriting machine, the combination with a carriage and tabulating mechanism including key levers, of a polychrome ribbon, ribbon shifting mechanism including a rocking frame with which said key levers coöperate to shift the ribbon shifting mechanism so as to enable printing in different colors. 100
15. In a typewriting machine, the combination with a carriage and tabulating mechanism including key levers, of a polychrome ribbon, ribbon shifting mechanism including a universal element, said key levers engaging with said universal element different 105ly to shift the ribbon mechanism so as to enable printing in different colors.
16. In a typewriting machine, the combination with a carriage and tabulating mechanism including key levers, of a polychrome ribbon, ribbon shifting mechanism includ- 110
17. In a typewriting machine, the combination with type keys, a traveling carriage, and a polychrome ribbon, of column-selecting key levers, and extensions on said column-selecting key levers which determine whether the type keys shall print in red or black. 115
18. In a typewriting machine, the combination with type keys, a traveling carriage, and polychrome ribbon, of tabulator keys, ribbon shifting mechanism under the control of said tabulator keys, the arrangement of parts being such that the printing color may be changed by said tabulator keys and manually changeable at will after having been shifted by said tabulator keys. 120
19. In a typewriting machine, the combination with a polychrome ribbon, of ribbon-shifting mechanism, carriage-positioning means, means adapted to shift said ribbon mechanism by positioning the carriage, and separate means for then shifting the ribbon mechanism to its first position without disturbing said positioning means. 125
20. In a typewriting machine, the combination with a polychrome ribbon, of ribbon shifting mechanism, tabulator mechanism including a series of key levers, means whereby said ribbon mechanism is variably shiftable by said key levers, and ribbon shift keys, the parts being so arranged that the ribbon mechanism may be shifted by either one of the ribbon shift keys without disturbing said tabulator key levers. 130
21. In a typewriting machine, the combination with a carriage, a tabulator including key levers, and a polychrome ribbon, of ribbon-shifting mechanism operated by said levers, lost-motion connections between said levers and said mechanism, and a finger-piece for positively shifting said mechanism. 135
22. In a typewriting machine, the combination with a carriage, a tabulator including key levers, and a polychrome ribbon, of ribbon-shifting mechanism, means normally out of touch with said levers, whereby the shifting mechanism is operated by said levers, and a manual device for operating said shifting mechanism, and adapted to reset it after the operation and return of any key lever. 140
23. In a typewriting machine, the combination with a carriage and a polychrome ribbon, of a tabulator for said carriage including key levers, ribbon shifting mechanism, and a member movable in one direction by certain of said key levers and in another direction by other of said key levers. 145

vers, said member being connected to said ribbon shifting mechanism.

24. In a typewriting machine, the combination with a carriage and a tabulator including a set of independently operable key levers, of a ribbon device, means on one of said tabulator key levers to shift said shiftable ribbon device, and means on another of said key levers to restore said ribbon device to its first position.

25. In a typewriting machine, the combination with a carriage and a tabulator comprising a series of key levers, of a ribbon shifting mechanism, a universal bar or frame extending along said series of key levers, certain of said key levers constructed to engage the forward portion, and certain of said key levers constructed to engage the rear portion of said universal bar to move the latter in opposite directions, a connection for said universal bar to said shiftable ribbon mechanism, and a detent to hold said

shiftable ribbon mechanism in various positions to which it is set by said universal bar.

25

26. In a typewriting machine, the combination of a carriage comprising a platen, a polychrome ribbon, keys for shifting said ribbon, a tabulator comprising keys, and a shiftable device connected to said ribbon shift key under the control of said tabulator keys.

30

27. In a typewriting machine, the combination with a carriage and a tabulator therefor, said tabulator comprising key levers, of an extension on one of said key levers, an extension on another of said key levers, ribbon mechanism, and means controlled by said extensions for varying the setting of said ribbon mechanism.
